UNITED STATES PATENT OFFICE.

WILLIAM J. M. HAMES, OF ATLANTA, GEORGIA.

CLEANING AND POLISHING DEVICE.

No. 817,766.

Specification of Letters Patent

Patented April 17, 1906.

Application filed August 16, 1905. Serial No. 274,432.

To all whom it may concern:

Be it known that I, WILLIAM J. M. HAMES, a citizen of the United States, residing at Atlanta, in the county of Fulton and State of Georgia, have invented a new and useful 5 Cleaning and Polishing Device, of which the following is a specification.

This invention relates to cleaning and polishing devices, and has for its object to provide an improved hand-operated device of this character which is designed for cleaning and polishing any character of surface—such, for instance, as wood, metal, stone, glass, and the like.

15 A still further object of the invention is to equip the same with a shoe for application to any of the working faces, so as to protect the same when the device is being used for cleansing purposes and to prevent the device from becoming wet or brought into contact with a cleansing preparation.

With these and other objects in view, the present invention consists in the combination and arrangement of parts, as will be hereinafter more fully described, shown in the accompanying drawings, and particularly pointed out in the appended claims; it being understood that changes in the form, proportion, size, and minor details may be 25 made within the scope of the claims without departing from the spirit or sacrificing any of the advantages of the invention.

In the accompanying drawings, Figure 1 is a perspective view of the body of a cleaning 35 and polishing device constructed in accordance with the features of the present invention. Fig. 2 is a cross-sectional view thereof of having the shoe applied to one of its faces. Fig. 3 is a detail perspective view of the shoe 40 removed. Fig. 4 is a perspective view showing the device having another form of shoe fitted thereto.

Like characters of reference designate corresponding parts in each and every figure of the drawings.

45 The body of the present device is polygonal in cross-section, so as to present a plurality of faces. While any cross-sectional shape may be employed according to the different characters of faces desired, I have 50 shown in the drawings a triangular body, the present embodiment including opposite duplicate triangular heads 1 and sides 2, 3, and 4, suitably connected to the edges of the 55 heads, and thereby completing a hollow tri-

angular body. The several sides or longitudinal faces of the body are provided with the respective facings 5, 6, and 7, each of which differs from the other and is in the nature of a flexible covering having its opposite longitudinal edges turned or folded inwardly between the edges of adjacent sides of the body and glued, clamped, or otherwise fixed therebetween. The material which may be employed for facing the sides of the body embraces a great variety—such, for instance, as cloth, felt, wood fiber, cotton, wool, jute, paper, hair, leather, sandpaper, and the like and combinations of such materials.

65 For convenience in handling the body there is provided a handle consisting of a shank or stem 8, which is provided with a yoke or fork 9, embracing the ends of the body, with the terminal of each fork member pivoted to the center of the adjacent head, as indicated 70 at 10, whereby the body may be turned upon its longitudinal axis to present any one of its faces to the surface to be cleaned or polished.

75 In connection with the body I employ a detachable shoe 11, (shown in Figs. 2 and 3 of the drawings,) said shoe consisting of a metallic plate of a size to cover one of the faces of the body and provided throughout its opposite longitudinal edges with inwardly-bent 80 spring-flanges 12, overhanging the shoe and 85 designed to frictionally embrace the body, as shown in Fig. 2, so as to detachably connect the shoe to the body. Each flange 12 is rebent upon its outer side to form an inverted substantially U-shaped clamp member with 90 the adjacent extremity of the plate extended laterally outward, as at 14, to form a guard-flange disposed in a plane above that of the main portion 11 of the shoe. The exposed surface of the shoe is provided with a suitable covering or facing 15 which is drawn tightly across the shoe and has its opposite edges inserted into the respective clamps 13, 95 whereby the material is detachably connected to the shoe, and may therefore be conveniently replaced when worn.

100 With this shoe in position, as shown in Fig. 2, the device is worked back and forth upon the work, to which water or any cleansing compound is applied, the shoe serving to take the wear, and thereby protecting the working faces of the body 6, while the guard-flanges 14 prevent water and the like from creeping up the front and rear sides of the shoe to the inactive working faces of the body of the device. 110

It will now be understood that the work may be first washed or cleansed by the use of the present device with the shoe attached thereto and afterward polished by the employment of one or more of the surfaces of the body of the device, the shoe of course having been previously removed.

A slightly-modified form of shoe has been shown in Fig. 4, which discloses a metallic body 16, having an upstanding flange 17 at each edge thereof, thereby producing a dished or concaved body having yieldable or elastic sides, between which the body of the device may be clamped in the manner shown in the drawings. This form of shoe is longer than the body of the device, so as to cover a greater area. Each longitudinal flange is bent outwardly and then inwardly to form a substantially U-shaped rim, which snugly embraces the adjacent edge of the material 19, which is stretched across the exposed surface of the shoe, each end flange being merely bent back upon its outer face, as at 20, to snugly embrace the adjacent edge portion of the facing material, so as to detachably connect the latter to the shoe.

In using the device with a shoe applied to the body the latter is worked back and forth in the well-known manner by manipulation 30 of the handle, so as to reciprocate the shoe upon the surface under treatment, and by reason of the polygonal cross-sectional shape of the body the latter is not liable to turn upon its axis when not in operation.

35 It is of course apparent that the body may be turned independently of the shoe, particularly in working upon a dry surface, and

therefore the body has been provided with the different facings 5, 6, and 7.

Having thus described the invention, what 40 is claimed is—

1. A device of the class described comprising a body, and a shoe having a work-face and provided with opposite spring-flanges sprung upon the body and detachably connecting the shoe thereto. 45

2. A device of the class described comprising a body, and a shoe having opposite spring-flanges detachably sprung upon the shoe, and a facing applied to the shoe with 50 the flanges bent around opposite edges of the facing to connect the same to the shoe.

3. A device of the class described comprising a body, and a detachable shoe having opposite spring-flanges detachably sprung upon the body, a working face for the shoe, and guard-flanges projecting laterally from the shoe. 55

4. A device of the class described comprising a body, and a shoe having opposite spring-flanges detachably sprung upon the body, each flange being rebent upon its outer side to form a U-shaped clamping member with the outer edge of the flange bent laterally outward to form a guard, and a facing applied 60 to the shoe with opposite edges secured within the clamp portions of the flanges. 65

In testimony that I claim the foregoing as my own I have hereto affixed my signature in the presence of two witnesses.

WILLIAM J. M. HAMES.
